UNITED STATES PATENT OFFICE.

LLOYD GARRISON, OF PORTLAND, OREGON.

DRILLING-MACHINE.

1,146,243.

Specification of Letters Patent. Patented July 13, 1915.

Application filed July 1, 1912, Serial No. 707,035. Renewed December 3, 1914. Serial No. 875,387.

To all whom it may concern:

Be it known that I, LLOYD GARRISON, citizen of the United States, residing at Portland, in the county of Multnomah and State 5 of Oregon, have invented certain new and useful Improvements in Drilling-Machines, of which the following is a specification, reference being had therein to the accompanying drawing.

10 This invention relates to drills, and has special reference to drills for drilling holes in ceilings, concrete structures and the like.

One of the principal objects of this invention is the production of an efficient stand- 15 ard which may be adjusted vertically to different height ceilings whereby the drill mechanism may be efficiently operated.

Another object of this invention is the 20 production of an efficient mechanism whereby a considerable amount of leverage may be obtained for causing the drill to be struck a severe blow whereby the drill may be efficiently driven into very hard substances.

With these and other objects in view, the 25 invention consists in general of certain combinations and arrangements of parts as will be hereinafter fully described, illustrated in the accompanying drawings, and specifically claimed.

30 In the drawings, Figure 1 is a side elevation of the drill. Fig. 2 is a rear elevation of a portion of the standard. Fig. 3 is a side elevation partly in section of the lower portion of the standard. Fig. 4 is an enlarged 35 side elevation partly in section of the upper portion of the standard. Fig. 5 is an enlarged sectional view of the spring connection for the hammer throwing rod. Fig. 6 is a side elevation partly in the section of 40 the connecting mechanism for the sections of the hammer throwing rod. Fig. 7 is a section taken on line 7—7 of Fig. 6. Fig. 8 is vertical section through the drill supporting member of the standard. Fig. 9 45 is a section taken on line 9—9 of Fig. 5. Fig. 10 is a detailed perspective of the foot operating lever. Fig. 11 is a detailed perspective of one end of one of the sections of the lever throwing rod.

50 By referring to the drawings by numerals, it will be seen that 1 designates the base which supports the primary portion 2 of the standard, and this primary portion 2 is threaded into the collar portion 3 of the 55 base 1. The base 1 is held upon the standard or supported by means of the ordinary

bolts or screws 4. The primary section 2 is provided with an upwardly extending threaded neck 5, which threaded neck is slidably mounted within the auxiliary section 6 of the standard. The auxiliary section 6 is provided upon each side with a longitudinally extending slot 7 in which works a guide pin 8, and this guide pin passes transversely through the threaded neck 5 and by means of this pin it will be seen that the auxiliary section 6 will be held against rotation relative to the primary section 2. A locking nut 9 is threaded upon the neck 5 and is adapted to be threaded so as to bind 70 against the lower edge of the auxiliary section 6 and hold the auxiliary section in an adjusted position relative to the primary section 2. A head 10 is threaded upon the upper end of the auxiliary section 6, and this head is provided with a longitudinally extending slot 11 in which is pivotally mounted the hammer or sledge 12. This hammer or sledge is supported upon a link member 13, which link member is pivotally 75 secured within the slot 11 by means of the pivot pin 14. The rear end of the hammer 12 extends rearwardly, and is connected to the primary section 15 of the hammer throwing rod by means of the link member 13. The hammer throwing rod also 80 comprises the auxiliary section 17, and the primary and auxiliary sections are provided at their adjacent ends with a toothed surface 18 whereby the two sections may be firmly 85 held in an adjusted relation. A clamp 19 is positioned upon the primary and auxiliary sections at their junction, and the sections are firmly clamped together by means of a thumb nut 20 for firmly holding the two 90 sections in their adjusted position. The lower end of the auxiliary section 17 is provided with a head 21, which head travels within a casing 22 supported by the auxiliary section 17. A coil spring 23 is positioned 95 upon the lower end of the auxiliary section 17, within the casing, and normally exerts a downward pressure upon the head 21 to normally force the head 21 toward the lower end of the casing 22. A link rod 24 is connected to the lower end of the casing 22 by 100 means of an enlarged head 25 which is threaded upon the upper end of the link rod 24, and the lower end of the link rod 24 is connected to the foot lever 26 as illustrated 105 in Fig. 1.

The primary section 2 of the standard is

provided with a lug 27 and upon this lug 27 is pivotally secured the foot lever 26 by means of the parallel ears 28. The foot lever 26 is provided centrally with a longitudinally extending aperture 29, and the lower end of the link rod 24 passes through this aperture and is secured to the foot lever by means of the pin 30, which pin passes through the apertures 31 formed in the foot lever 26. An upwardly extending lip 32 is formed upon the foot lever 26 so as to limit the upward movement of the foot lever relative to the link rod 24.

The head 10 is provided with an eye 33, which eye is threaded to receive the threaded arm 34. This arm 34 carries a casing 35 at its outer end, and this casing 35 is provided with a central aperture 36. A plug 37 is threaded in the lower end of the aperture 36, and a plunger 38 is slidably mounted in said plug and carries an enlarged head 39. A collar 41 is carried by the plunger 38 and a spring 40 is interposed between said collar 41 and a shoulder 41' projecting inwardly from the walls of the aperture 36 just below the head 39. The spring thus serves to hold the collar 41 against the plug 37 and hence to return the plunger after each stroke of the hammer. A filler 42 is threaded in the upper end of the aperture 36 and is adapted to support the drill 43 which passes through the filler 42 and rests upon the upper head 39 of the plunger 38.

From the foregoing description it will be seen that as the foot lever 26 is depressed, the hammer will be forced upwardly so as to engage the lower end of the plunger 38 which will, of course, drive the drill or bit 43 upwardly. It will be seen that owing to

the amount of leverage which is obtained by 49 the mechanism set forth, a severe blow will be struck upon the lower end of the plunger 38 thereby causing the drill or bit 43 to be driven into the ceiling. It will further be seen that owing to the yieldable connection 45 between the auxiliary and primary sections of the lever throwing rod the hammer will be allowed to rebound after once striking the lower end of the plunger. It will be further seen that the upwardly extending 50 lug 32 not only constitutes a means for limiting the upward swinging of the foot lever 26, but also constitutes a toe stop to limit the movement of the foot upon the lever. A handle 43^a may be employed for attaching 55 to the drill 43 whereby the drill may be conveniently inserted and removed from the drill supporting casing.

Having thus described the invention, what is claimed as new, is:—

A drilling machine of the class described comprising a primary standard and an auxiliary standard adjustably mounted thereon, a head carried by said auxiliary standard and provided with a slot formed therein, a link member pivotally mounted within said slot, a hammer for said link member, means associated with said link member for holding said link member within said slot and means for causing said hammer to be actuated.

In testimony whereof I hereunto affix my signature in presence of two witnesses.

LLOYD GARRISON.
